UNITED STATES PATENT OFFICE.

RICHARD PATTISON, OF NEW YORK, N. Y.

STEAM-INJECTOR.

SPECIFICATION forming part of Letters Patent No. 599,473, dated February 22, 1898.

Application filed January 19, 1897. Serial No. 619,714. (Model.)

To all whom it may concern:

Be it known that I, RICHARD PATTISON, of New York, in the county and State of New York, have invented a new and useful Improvement in Steam-Injectors, of which the following is a specification.

This invention relates to an improvement in steam-injectors, and more particularly to that class known as "double-jet" or "lifting and forcing" injectors.

One object of this invention is to provide an injector of the above class in which the admission of steam to both the lifting and forcing chambers is controlled by a single valve, thereby doing away with the necessity of providing the steam-inlet pipe with a valve.

Another object is to provide an injector in which the pressure is very low in the overflow-port of the forcing-chamber relative to the pressure in the boiler and in which water at a very high temperature may be successfully lifted into the injector and forced therefrom into the boiler.

A further object is to provide means for preventing the "setting" of the valve in its seat.

A still further object is to provide means for insuring a thoroughly steam-tight valve.

A practical embodiment of my invention is represented in the accompanying drawings, in which—

Figure 1 represents an outside view of the injector, the valve-operating handle being shown in full lines in the position which it assumes when the admission of steam to the injector is entirely cut off and in dotted lines in the two positions which it assumes, first, when the steam is admitted to the forcing-chamber only by way of the lifting-chamber, communication being established from the forcing-chamber to the overflow-chamber, and, second, in the position which it assumes when the valve has shut off communication to the overflow-chamber and opened communication directly to the forcing-chamber and also to the lifting-chamber. Fig. 2 is an outside view of the reverse side of the injector from that shown in Fig. 1. Fig. 3 is a vertical longitudinal central section through the injector, the valve or cock being shown in its closed position. Fig. 4 is a detailed view showing the position of the cock when steam

is admitted to the lifting-chamber and not directly to the forcing-chamber. Fig. 5 is a similar view showing the position of the cock with full open communication being established from the steam-inlet directly to both the lifting-chamber and the forcing-chamber, and Fig. 6 is a horizontal section on the line 6 of Fig. 1.

The injector-casing is denoted as a whole by A, and it is provided with a steam-inlet a, a water-inlet a', and a discharge opening or outlet a'' for attachment thereto of a pipe or tube leading to the boiler.

The steam-chamber is denoted by B, the lifting-chamber by C, the forcing-chamber by D, and the overflow-chamber by E. The injector-casing is further provided with a suitable valve-seat f, to which is fitted a rotary valve or cock F, having a suitable stem f' uprising therefrom, to which is attached a suitable operating-handle f'' for turning the said valve or cock.

The steam-inlet a is provided with a suitable port a³, communicating with the valve-seat f. The steam-chamber B is provided with a suitable port b, communicating with the valve-seat f a short distance from the port a³. The overflow-chamber is provided with a port e, communicating with the valve-seat f, and adjacent to the said port e is located a suitable port d, opening from the valve-seat f into the forcing-chamber D. Another port d' opens from the valve-seat f into the forcing-chamber D through the force-nozzle, to be hereinafter described.

The lifting-chamber C communicates with the forcing-chamber D through a lifting-tube G, and the steam-chamber B connects with the lifting-chamber C through a steam-nozzle g, which nozzle g is located in position to direct the steam into the lifting-tube G for lifting the water into the forcing-chamber D. A forcing-tube H is located in the forcing-chamber D, and a steam-nozzle h is located in position to direct the steam which enters the port d' when the valve F is full open into the forcing-tube H for forcing the water within the forcing-chamber D into the boiler.

The valve F is provided with a suitable through-port f³, which port is considerably larger at one side of the valve and is gradually reduced through to the other side of the

valve. The valve F is further provided with a suitable port f^4 , which is adapted to open communication between the forcing-chamber D and the overflow-chamber E, through the 5 ports d and e, when the valve is in a position part way between "full closed" and "full open," the said position being shown clearly in Fig. 4.

The valve F is inserted into its seat f through 10 the casing A, and is held against its seat and at the same time rendered steam-tight by the following device: A yielding packing I is inserted into position surrounding the valve-stem f', between two plates J and K. A circumferential flange L extends outwardly from 15 the casing A, which flange is screw-threaded upon its exterior and has a smooth bore. The plates J and K are slightly smaller than the bore of the flange L and the packing I is 20 adapted to fit the said bore quite snugly. The plate K is of sufficient thickness to project a slight distance outside the outer end of the flange L when the parts are in position. A clamping-nut M surrounds the valve-stem f' 25 and has a screw-threaded engagement with the exterior of the flange L. The top of the nut M engages the plate K as the nut is screwed inwardly, and the further inward movement of the nut M serves to yieldingly 30 force the valve F down into its seat f and at the same time compress the yielding packing I and thereby force it snugly against the bore of the flange L.

To prevent the valve F from sticking under 35 the pressure of steam, I provide a chamber N beneath the valve and admit steam thereto through a suitable duct f^5 , leading from the through-port or passage-way f^3 . The steam within the chamber N will tend to lift the valve 40 away from its seat f and thereby allow it to be freely turned. The chamber N is shown in the present instance as formed in a screw-cap O, which has a screw-threaded engagement with a circumferential flange P of the casing A.

45 The casing A is provided with another circumferential flange Q, with which a cap R has a screw-threaded engagement. Access to the steam-nozzle g and lifting-tube G is gained by removing the cap R. The casing A is 50 still further provided with a pair of stops a^4 a^5 for limiting the movements of the valve-operating handle.

The operation of my invention is as follows: Supposing that the valve be closed, as shown 55 in Figs. 1 and 3, and it is desired to force water into the boiler, the valve-operating handle f^2 is swung around until the valve is in the position shown in Fig. 4, in which the port f^4 has open communication between the forcing-chamber D and the overflow-chamber E, and the port f^3 has open communication 60 between the steam-inlet a and the steam-chamber B. The steam thus admitted into the steam-chamber B will pass through the 65 nozzle g into the lifting-tube G and thereby lift the water into the chamber C, from thence into the forcing-chamber D and from thence

into the overflow-chamber E. As soon as the water is seen to escape from the overflow E the movement of the valve-operating handle 70 is continued until stopped by the stop a^5 , when the valve will be in the position shown in Fig. 5, in which the communication between the forcing-chamber D and the overflow E is cut off and direct communication 75 established through the passage-way f^3 and port d' into the forcing-chamber D, communication at the same time being still obtained from the inlet a into the steam-chamber B. In this position the valve is full open and 80 steam is being admitted through the nozzle g into the lifting-tube G, serving to lift the water into the chamber D and also through the nozzle h into the forcing-tube H for forcing the water within the chamber D out 85 through the discharge end of the injector to the boiler.

It will be seen from the above description that the admission of steam is thoroughly controlled by the single valve, the handle of the 90 valve at the same time being caused to pass through an arc of only about ninety degrees between its extreme limits of movement. It will further be seen that the injector as above described consists of a very few parts and 95 also that the parts are so arranged that the liability of the steam wearing them to a considerable degree is reduced to a minimum. The steam nozzles and tubes are so arranged that they may be readily removed from the 100 injector, and the wear upon the valve may be very quickly and easily taken up when so desired.

The arrangement of the several chambers and parts is such that the pressure is very 105 low at the forcing-chamber D when the injector is working, and also the injector is capable by reason of the arrangement of the lifting and forcing tubes to feed very hot water to the boiler when so desired.

110 It is evident that slight changes may be resorted to in the construction and arrangement of the several parts without departing from the spirit and scope of my invention. Hence I do not wish to limit myself strictly 115 to the structure herein set forth; but

What I claim is—

1. In an injector, a casing having a rotary valve seated therein in the rear of the forcer, the said casing being provided with a steam- 120 inlet, a lifting-chamber, an overflow-chamber and a forcing-chamber, all in direct communication with the face of the valve, the said valve being provided with two ports, one for opening and closing communication between the steam-inlet and the lifting-chamber, and between the steam-inlet and forcing-chamber, and the other port for opening and 125 closing communication between the forcing-chamber and the overflow-chamber, substantially as set forth.

2. In an injector a casing having a rotary valve seated therein in the rear of the forcer, the said casing being provided with a steam-

inlet, a steam-chamber, an overflow-chamber and a forcing-chamber all leading directly to the face of the valve, and a lifting-chamber communicating with the steam-chamber and 5 forcing-chamber; the said valve being provided with a port adapted to open communication between the steam-inlet and the steam-chamber and between the steam-inlet and the forcing-chamber, and with a second port for 10 opening and closing communication between the forcing-chamber and the overflow-chamber, substantially as set forth.

3. In an injector the combination with a 15 casing having a valve-seat therein, and a steam-chamber located below the valve-seat, of a rotary valve arranged to turn in said seat the said valve having a steam port or passage-way therein and a duct leading from 20 said steam-port to the steam-chamber where-
by the pressure of steam will tend to lift the

valve and means for positively forcing the valve downwardly, substantially as set forth.

4. In an injector the combination with a 25 casing provided with a steam-inlet, a lifting-chamber, an overflow-chamber and a forcing-chamber having an overflow-port and a steam-inlet port, of a valve seated within the casing in the rear of the forceer having a port adapted to open direct communication between the steam-inlet and the lifting-chamber, between 30 the steam-inlet and the inlet-port of the forcing-chamber and a second port to open and close communication between the overflow-port of the forcing-chamber and the overflow-chamber, substantially as set forth.
